United States Patent

Des. 240,160

Patented June 1, 1976

240,160

APERTURE CARD VIEWER

Thomas C. Langdon, Columbia, Md., and James H. Slat,
Rochester, N.Y., assignors to Eastman Kodak Com-
pany, Rochester, N.Y.

Filed Mar. 14, 1974, Ser. No. 451,242

Term of patent 14 years

Int. Cl. D16—02

U.S. Cl. D16—15

FIG. 1

FIG. 2

FIG. 5

FIG. 6

FIG. 7

FIG. 1 is a top plan view of an aperture card viewer showing our new design;

FIG. 2 is a left side elevational view thereof;

FIG. 3 is a bottom plan view thereof;

FIG. 4 is a left side elevational view of FIG. 3;

FIG. 5 is a rear elevational view thereof;

FIG. 6 is a front elevational view thereof; and

FIG. 7 is a rear, top, right-side, perspective view thereof.

We claim:

The ornamental design for an aperture card viewer, substantially as shown.
